APPARATUS FOR APPLYING LABELS
TO SPOOLSRolland B. Lange, Muskegon, Mich., assignor to
Anaconda Wire and Cable Company, a corpora-
tion of Delaware

Application January 14, 1949, Serial No. 70,988

9 Claims. (Cl. 216—9)

1

This invention provides improved apparatus for applying a label to the periphery of a spool, and especially for commercially applying labels to spools which may vary considerably in diameter in the region where the label is applied. The apparatus is especially suited for wrapping protective labels peripherally about spools of fine magnet wire. The label, of course, serves the additional purpose of carrying markings showing the size and nature of the wire, the name of the manufacturer, etc.

When magnet wire is packaged on spools, it is desirable to apply a paper label to the periphery of the spool so as to cover up and protect the wire from damage. Many ingenious machines have been devised for applying labels peripherally to spools and other cylindrical objects, but the machines heretofore used successfully for this purpose have been designed to operate on spools or containers of uniform diameter. No thoroughly satisfactory machine for applying labels to magnet wire packaged on spools has heretofore been devised, because in the magnet wire industry the amount of wire on a spool may vary over quite wide limits, and consequently the diameter of the package of wire on the spool is quite variable. The label should be pulled up tightly about the wire on the spool in order to afford maximum protection, so the label-applying machine must be of such nature as to wrap the label tightly regardless of the diameter of the spool package to which it is applied.

The label-applying machine of the invention meets the foregoing requirements. The principal features of the new machine are the label guide by which the label is guided into position peripherally about the spool, and the mechanism by which the label then is wrapped about the spool. The label guide of the new apparatus has a substantially cylindrical section and a substantially plane section extending tangentially therefrom, with a narrow opening at the juncture of the cylindrical and plane sections for insertion of a label into the interior of the cylindrical section. The cylindrical section further is formed with at least two slots of length somewhat less than the width of a label, and of considerable width (the angular width of the slots may well be 90° or more, measured from the axis of the cylinder). The slots are substantially centrally positioned along the length of the cylinder so as to leave a pair of substantially full cylindrical guide shoes, which are spaced from each other on a common axis, at each end of the cylinder. The label guide may be made by suitably bending and cutting a

2

single sheet of metal or other material, or it may be built up from several separately formed components defining the plane section and the cylindrical guide shoes.

- 5 The inside diameter of the cylindrical section of the label guide is only slightly larger than the diameter of the flanges of the spool, and provision is made for introducing a spool to be labeled axially into the interior thereof. The plane section of the label guide serves to guide a label into contact with the inner surfaces of the guide shoes, and these in turn serve to guide the label into cylindrical form about the periphery of a spool to be labeled, the outer surface of the label 10 being exposed through the slots so that a rotative force may be applied to it for wrapping it about the spool.
- The mechanism by which the label thus guided into position about the spool is wrapped in place 15 thereon comprises a pair of endless belts each rotatably mounted on rollers whose axes are parallel to the common axis of the guide shoes. The belts are positioned so as to face the slots in the cylindrical section of the label guide, and 20 are mounted so that they may be swung, in a plane perpendicular to the axis of the guide shoes, broadside through the slots into and away from frictional engagement with the periphery of a spool positioned inside the guide shoes. When 25 the belts are rotated and pressed against the spool, they serve to wrap a label, guided into position by the label guide, about the periphery of the spool within the guide shoes. At the same time, of course, they serve to rotate the spool 30 about its axis. If the belts are held in engagement with the label on the spool for the length of time required for the spool to make several complete revolutions, the label is drawn up snugly against the wire packaged thereon, regardless of the diameter of such package; and if 35 a suitable adhesive has been applied to the label, it is held thereby in position about the spool even after the belts are released by swinging them away from the spool. Then the labeled spool may 40 be removed axially from within the label guide, and a new spool may be introduced.

A machine in which the improved label guide and label-wrapping mechanism of the invention are incorporated is described in greater detail 45 below in conjunction with the accompanying drawings, in which:

Fig. 1 is side view, partially in section, of the machine of the invention;

Fig. 2 is a plan of the machine shown in Fig. 1;

Fig. 3 is a horizontal section taken substan-

3

tially along the line 3—3 of Fig. 1, showing the lever mechanism by which the belts are swung into and away from frictional engagement with the periphery of a spool to be labeled;

Figs. 4 and 5 are horizontal sections taken substantially along the line 4—4 of Fig. 1, showing the label-wrapping belts in two different positions;

Fig. 6 is a vertical section taken substantially along the line 6—6 of Fig. 3, showing a spool in position to have a label applied;

Fig. 7 is an isometric view of the label guide;

Fig. 8 is a plan of a label showing a preferred location of the application of adhesive thereto; and

Fig. 9 is a view of a labeled spool of wire.

Referring to Fig. 1, the machine stands on a base 10 and comprises a spool feeding deck 11 supported above the base, along which each spool 12 is fed into position to have a label applied. A label guide and label-wrapping mechanism 13 is mounted above the spool feeding deck on the underside of a supporting frame 14, and above this frame is a table 15 carrying the motor drive for the apparatus.

The label guide 16 is shown separately from the machine as a whole in Fig. 7, and its position in the machine is apparent from Figs. 1, 4, 5 and 6. It comprises a plane section 17 tangentially connected to a cylindrical section 18. It is conveniently formed by bending one end 19 of a sheet of smooth metal or other suitable material around in the form of a cylinder, leaving unbent the portion of the sheet that is to form the plane section 17. The inside diameter of the cylindrical section is just a little greater than the diameter of the end flanges of the spool 12. The bent end 19 of the cylindrical section is not quite closed against the plane section 17, but instead a narrow aperture 20 is left between them. The cylindrical section 18 is formed with two wide slots 21 diametrically opposite each other (the angular width of these slots is indicated by the angle A in Figs. 4 and 7 and advantageously exceeds 90°). The slots are of a length, measured along the length of the cylindrical section 18, that is somewhat less than the width of a label, and they are approximately centered along the length of the cylinder so as to leave two substantially full cylindrical guide shoes 22, which are spaced from each other along a common axis, at the ends of the cylindrical section.

The plane section 17 of the label guide serves to guide a label through the aperture 20 into contact with the inner surface of the cylindrical section 18, and this latter section serves to guide the label into cylindrical form about the periphery of the spool to which it is to be applied. To facilitate this guiding action, the plane and cylindrical sections of the label guide both are provided at the top and at the bottom with guide rails 23 to insure that the label will be delivered into the cylindrical section in centered relation between the ends thereof. Additionally, the plane section 17 is provided with guide ways 24 to prevent the label from falling out once it has been inserted. The rails 23 are spaced apart a distance just a little greater than the width of a label, and the guide ways 24 are spaced by these rails from the body of the plane section 17 by a distance enough greater than the thickness of the label so that the label may be slid easily along the plane section behind the guide ways into en-

4

gagement with the inner surfaces of the cylindrical guide shoes 22.

From the foregoing it is apparent that a spool must be positioned within the cylindrical section 18 of the label guide so that a label guided thereby into cylindrical form may be wrapped about the periphery of the spool. This is accomplished by providing for introduction of one spool at a time axially into the interior of this cylindrical section. The mechanism for doing so is best shown in Figs. 1 and 6. The spool 12 to be labeled is delivered along the deck 11 to the position where its hollow barrel is approximately centered over a vertically movable turntable 25. The turntable is carried on the upper end of a vertical shaft 26 supported in bearings 27 and 28. The label guide is secured to the supporting frame 14 in such position that the axis of its cylindrical section 18 coincides with a projection of the axis of the turntable 25. A lever 29 pivotally connected to a fixed support 30 and to the shaft 26 provides for lifting the turntable from a position just below the spool feed deck 11 (as shown in full lines in Fig. 1) to an elevated position where when it just enters the lower guide shoe of the cylindrical section of the label guide (as shown in dotted lines in Fig. 1 and in full lines in Fig. 6). A latch 31 is provided to hold the shaft 26 in its elevated position.

The turntable 25 is formed with an upwardly projecting centering pin 32 so that when a spool 12 is moved along the feed deck 11 to a position approximately centered over the turntable and the lever 29 is then raised, the spool is automatically centered on the turntable and is lifted axially into position within the cylindrical section of the label guide. The spool is held from tilting when in its elevated position by a pilot pin 33 secured to the supporting frame 14 on the axis of the cylindrical section of the label guide. In its elevated position, the spool is free to rotate about its axis on the turntable.

The mechanism by which a label delivered through the label guide is wrapped about the periphery of a spool supported by the turntable 25 centrally within the cylindrical section of the label guide is best shown in Figs. 3 to 6. It comprises a pair of soft endless belts 35 (advantageously of rubber), each of which is carried on a pair of rollers 36 and 37. Each pair of rollers is supported between upper and lower members 38 of a roller frame with their axes parallel to the axis of the cylindrical section 18 of the label guide. The roller frame members 38 are pivotally mounted on shafts 39 and 40, which shafts are supported at their upper ends by the supporting frame 14 and are steadied at their lower ends by frame elements 41 depending from the supporting frame 14. (The frame elements 41 further serve to hold the label guide securely in position.) The shafts 39 and 40 are secured axially to the rollers 36, which are the driving rollers for the belts 35. The other rollers 37 are idling rollers for holding the belts taut and in position.

The position in which each roller frame is supported on its pivot shaft 39 is such that the broad face of each belt 35, midway between the rollers, lies directly opposite the wide openings 21 in the cylindrical section 18 of the label guide. The belts are a trifle narrower than the length of the slots 21, and therefore the belts may be swung broadside through these slots, into and away from frictional engagement with the periphery of a spool positioned inside the cylindrical section 75 of the label guide, by movement of the roller

frame members 38 about their pivot on the shafts 39 and 40. Fig. 4 shows the belts swung out and away from engagement with a spool inside the cylindrical section of the label guide, and Fig. 5 shows them swung in through the slots and in engagement with the spool.

A lever system is provided for swinging the roller frame members 38 simultaneously toward or away from engagement with a spool in position to receive a label. This lever system, best shown in Figs. 2 and 3, comprises a main control lever 42 pivotally mounted for movement through a small angle about the axis of the cylindrical section of the label guide. It is conveniently pivoted on an upward projection 43 of the pilot pin 33 (Fig. 6). An extension of this lever projecting beyond the supporting frame 14 provides a handle 44 for manipulating it. Two links 45 are pivotally connected to the lever 42, on opposite sides of and equidistant from the axis about which the lever 42 moves. Each of these links is pivotally connected at the end remote from the lever 42 to the center portion of one of a pair of motion multiplying levers 46. One end of each of these latter levers is connected to a fixed pivot 47 on the frame of the machine, and the other end of each is pivotally connected (through a vertical arm 48', shown in Fig. 1) to the end of one of a second pair of links 48. The other ends of the latter links 48 are pivotally connected to a spreader bar 38' (Fig. 1) joining the upper and lower roller frame members 38. This lever system is such that when the handle 44 of the main lever 42 is swung to the left (the position shown in full lines in Fig. 3), the roller frames are swung about their pivotal mountings on the shafts 39 and 40 away from a spool inside the cylindrical section 18 of the label guide, and the belts 35 are thereby disengaged from frictional engagement with the periphery of the spool (the belts then are in the position shown in Fig. 4). When the handle 44 is swung to the right (the position indicated by the dotted lines in Fig. 3), the roller frames are swung in toward a spool positioned axially within the cylindrical section 18 of the label guide, and the belts 35 are moved broadside through the slots 21 into frictional engagement with the periphery of the spool (taking the position shown in Fig. 5).

If, when the belts are swung into frictional engagement with a spool in position for receiving a label, they are rotated on their rollers 36 and 37, and if at the same time a label is fed in through the plane section 17 of the label guide, it is apparent that the belts will rotate the spool and wrap the label therearound. A motor drive (best shown in Figs. 1 and 2) is provided for rotating the belts. This drive comprises a motor 50 bolted to the motor table 15 and driving a bevel gear 51 through a speed reducer 52. The bevel gear 51 on the output shaft from the speed reducer meshes with a corresponding bevel gear 53 mounted on the end of the shaft 40 to which one of the belt-driving rollers 36 is secured. Also mounted on this shaft is a sprocket wheel 54 connected by a sprocket chain 55 to a second similar sprocket wheel 56 secured to the shaft 39 on which the other driving roller is mounted. When the motor is energized, both shafts 39 and 40 are rotated thereby at the same speed, and in consequence the two belts are rotated at the same linear speed on their supporting rollers. The drive serves to rotate both belts in such direction that they cooperate to rotate a spool with which they are in

frictional engagement through the slots 21 in the cylindrical section of the label guide.

Sometimes it is advantageous to have the belts not rotating while they are swung into frictional engagement with a label to be applied to a spool, and to set them in motion only after such frictional engagement has been made. This is accomplished by providing in the motor circuit a switch 57 (Fig. 1) that is normally opened but that is closed when a plunger 59 is depressed. The lever handle 44 by which the rollers are swung into engagement with the periphery of the spool to be labeled is provided with a leaf spring cam 60 which closes the switch 57 when the lever has been thrown over to the position in which the belts engage the spool. Thus the motor is started after the belts engage with the spool and is stopped again when the belts are disengaged from the spool.

Operation of the apparatus is as follows: A spool 12 to be labeled is slid along the deck 11 into the position shown in full lines in Fig. 1, where its barrel overlies the turntable 25. The lever 29 is then raised to the position shown in dotted lines in Fig. 1, thereby lifting the spool axially into the interior of the cylindrical section 18 of the label guide. A label of width about equal to the length of the spool and of sufficient length so that its ends overlap when wrapped around the periphery of the spool is inserted into the plane section 17 of the label guide, its edges being supported by the guide ways 24. The label is inserted in such manner that the face carrying the printed data is toward the body of the label guide, and two or more spots 61 of an adhesive are applied on its back surface near its tail end (the end last entering the label guide). Suitable locations for the two spots of adhesive on the back surface of a label 62 are shown in Fig. 8. The adhesive should, of course, be applied far enough in from the side edges of the label so that it does not smear on the guide ways 24, and it is advantageous to apply it far enough in from the tail end 63 of the label so that after the label has been wrapped around the spool the tail end will serve as a tab by which the label can readily be removed.

It is only necessary that the label be inserted far enough into the label guide so that its entering end 64 passes about to the midpoint of the first opening 21 in the cylindrical section 18, although it may be inserted as much farther as desired. Next, the lever 44 is swung in the proper direction (to the right, as shown in Fig. 3) and to the extent necessary to cause the belts 35 to press against the outer surface of the label (or the periphery of the spool) where it is exposed through the openings 21. At the same time, the switch 57 is closed and the motor is thereby energized to rotate the belts in the direction indicated by the dotted arrows in Fig. 3. The frictional engagement of the belts with the label causes it to be wrapped about the periphery of the spool, the spool being rotated at the same time. By holding the belts in this label-applying position long enough for the spool to make several complete revolutions, the label is drawn up tightly about the wire or other material packaged on the spool, regardless of the amount of wire on the spool and hence the effective diameter of the package. The adhesive used should, of course, be one which sets quickly (a smooth flour paste is one adhesive that has been used successfully), so that when the lever 44 is returned to its original position, disengaging the belts from the spool, the label is held tightly in place about the pe-

riphery of the spool. Next the lever 29 is released, lowering the now labeled spool axially from within the cylindrical section of the label guide. It is removed from the deck 11, a new spool to be labeled is brought into position over the turntable 25, and the sequence of operation is repeated.

The form of machine herein shown is designed for manual operation of the levers 29 and 44, manual insertion and withdrawal of the spools, and manual insertion of the label into the plane section 17 of the label guide. However, attachments may be made to the machine for automatically feeding the spools and the labels, and for automatically operating the levers 29 and 44 in proper sequence. Mechanism for such automatic operation forms no part of the present invention, which is directed especially to the means by which the label is guided into position about the spool and is wrapped tightly thereon regardless of the diameter of the package of wire or other material on the spool.

Fig. 9 shows a spool as it appears after having been labeled by means of the apparatus of the invention. The label 62 is drawn tightly about the periphery of the package of wire on the spool, between the spool flanges 65, and is held in such position by the spots of adhesive 61. The tail end 64 of the label where it projects slightly beyond the spots of adhesive forms a convenient tab for stripping the label from the spool when the material thereon is to be exposed for use. Until such time the label effectively protects the fine enamelled wire or other easily injured product packaged on the spool from mechanical injury.

I claim:

1. Apparatus for applying a label to the periphery of a spool comprising a label guide having a pair of cylindrical guide shoes spaced apart on a common axis and each having an inside diameter only slightly greater than the diameter of the spool flanges, said guide shoes being spaced apart a distance somewhat less than the width of a label and being formed with an opening through which a label may be inserted into contact with the inside faces thereof, means for introducing a spool axially into the interior of said guide shoes, and a pair of soft endless belts of width less than the axial spacing between the guide shoes each mounted on a pair of spaced rollers, having axes parallel to the axis of the guide shoes, the belts between the supporting rollers being movable laterally in a plane perpendicular to the axis of the rollers in the space between the guide shoes into and away from engagement with the periphery of a spool positioned inside the guide shoes, whereby the belts may be brought into contact with a label inserted into the guide shoes for wrapping said label tightly about a spool positioned axially within said shoes.

2. Apparatus for applying a label to the periphery of a spool comprising a cylindrical label guide of inside diameter only slightly larger than the diameter of the spool flanges and of length approximately equal to the length of the spool; said cylindrical guide having a pair of wide substantially diametrically opposed slots of length somewhat less than the width of the label, the slots being approximately centrally disposed along the length of the cylinder so as to leave a pair of substantially full cylindrical guide shoes at the ends thereof, and said cylindrical guide further being formed with an opening for intro-

5. ducing a label tangentially into the interior thereof, means for introducing a spool to be labeled axially into said cylindrical guide, and a pair of soft endless belts each mounted and rotatable on a pair of rollers having axes parallel to the axis of the cylindrical guide, said belts being of a width somewhat less than the length of the aforesaid slots and being movable broadside in a plane perpendicular to the axis of the cylindrical guide through the slots into and away from engagement with the periphery of a spool positioned inside said guide, whereby the belts may be brought into contact with a label inserted tangentially into the cylindrical guide for wrapping said label tightly about the periphery of a spool positioned therein.

3. In apparatus for applying a label to the periphery of a spool, a label guide having a substantially plane section and a pair of substantially cylindrical guide shoes mounted tangentially at one end of said plane section, said guide shoes adjoining the plane section at its sides and being spaced apart on a common axis by a distance somewhat less than the width of a label, the label guide being formed with an aperture at the juncture of the plane section with the guide shoes through which a label may be passed from the plane section tangentially into contact with the inside surfaces of the guide shoes, means for introducing a spool to be labeled axially into the guide shoes, and a pair of soft endless belts rotatable on rollers whose axes are parallel to the axis of the guide shoes and movable in a plane perpendicular to the axis of the guide shoes in the space between said shoes broadside into and away from frictional engagement with the periphery of a spool positioned within the guide shoes, whereby said belts may be brought into contact with a label inserted into the interior of the guide shoes for wrapping said label tightly about the periphery of a spool positioned therein.

4. In apparatus for applying a label to the periphery of a spool, a label guide having a substantially cylindrical section and a substantially plane section extending substantially tangentially therefrom, said guide having an opening at the juncture of the cylindrical and plane sections for insertion of a label tangentially into the interior of the cylindrical section, means for introducing a spool to be labeled axially into said cylindrical section, the cylindrical section being formed with at least two wide apertures of length less than the width of a label through which the periphery of a spool positioned inside said cylindrical section is exposed, and at least two endless belts of soft material of width less than the length of said slots mounted and rotatable on rollers whose axes are parallel to the axis of said cylindrical section, said belts being each movable laterally in a plane perpendicular to the axis of the cylindrical section through one of said slots into and away from frictional engagement with the periphery of a spool supported axially within said cylindrical section, whereby said belts may be brought into contact with a label inserted into the cylindrical section of the label guide for wrapping said label tightly about the periphery of a spool positioned therein.

5. A label guide for guiding a label into position to be wrapped about the periphery of a spool comprising a substantially plane section and a pair of cylindrical guide shoes connected substantially tangentially to the plane section at one end thereof adjacent its side edges, said guide shoes being spaced apart on a common axis by a distance somewhat less than the width of a label

and each having an inside diameter only slightly greater than the diameter of the spool flanges, said label guide having a narrow aperture where the plane section adjoins the guide shoes and through which a label may be guided by the plane section into contact with the inner surfaces of the guide shoes.

6. A label guide for guiding a label into position to be wrapped about the periphery of a spool comprising a smooth metallic sheet bent to form a cylindrical section from which a plane section extends tangentially, the cylindrical section having an inside diameter only slightly larger than the diameter of the spool flanges and being not quite completely closed against the plane section, whereby a narrow aperture is provided through which a label may be guided by the plane section into contact with the inner surface of the cylindrical section, the cylindrical section being formed with a pair of wide slots of length somewhat less than the width of a label located midway between the ends of said cylindrical section, whereby the face of a label in said cylindrical section is exposed through said slots for the application thereto of a rotative force for wrapping it about the periphery of a spool positioned within said cylindrical section.

7. In apparatus for applying a label to the periphery of a spool, a cylindrical guide for guiding a label into cylindrical form about a spool in position to be labeled, and means for wrapping the label tightly against the periphery of such spool comprising a pair of endless belts each mounted on a pair of rollers whose axes are parallel to the axis of the spool, each pair of rollers being supported in a frame which is pivotally mounted to swing in a plane perpendicular to the axis of the spool, said frames being disposed on opposite sides of the spool, a lever system for swinging the frames on said pivotal mounting toward and away from the spool, whereby the faces of the belts may be frictionally engaged with and disengaged from a label in position to be applied about the periphery of the spool, and motive means for rotating the belts on the rollers while the belts are in frictional engagement with a label on the spool.

8. In apparatus for applying a label to the periphery of a spool, a cylindrical guide for guiding a label into cylindrical form about a spool in position to be labeled, and means for wrapping

the label tightly against the periphery of such spool comprising a pair of endless belts each mounted on a pair of rollers whose axes are parallel to the axis of the spool, a roller frame supporting each pair of rollers and holding them spaced apart sufficiently to keep the belt taut, each roller frame being pivoted on the axis of one of the rollers to swing in a plane perpendicular to the axis of the spool, said frames being disposed on opposite sides of the spool, a lever system for swinging the frames on their pivots toward and away from the spool, whereby the faces of the belts may be frictionally engaged with and disengaged from a label in position to be applied about the periphery of the spool, and motive means for rotating the belts on the rollers while the belts are in frictional engagement with a label on the spool.

9. In apparatus for applying a label to the periphery of a spool, a cylindrical guide for guiding a label into cylindrical form about a spool in position to be labeled, and means for wrapping the label tightly against the periphery of such spool comprising a pair of endless belts each mounted on a pair of spaced rollers whose axes are parallel to the axis of the spool, a roller frame supporting each pair of rollers in their spaced relation, a roller shaft secured to one roller of each pair on the axis thereof and projecting beyond the roller frame, the roller frames being pivotally mounted on said shafts for swinging in a plane perpendicular to the axis of the spool, each pair of rollers in its respective frame being disposed on opposite sides of the spool, a lever system for swinging the frames simultaneously about their pivots both toward and away from the spool, whereby the faces of the belts at points between the rollers may be frictionally engaged with and disengaged from a label in position to be applied about the periphery of the spool, drive wheels on each of the projecting roller shafts and drive means interconnecting said wheels, and motive means for rotating the thus interconnected roller shafts and thereby rotating the belts on the rollers while the belts are in frictional engagement with a label on the spool.
